(57) **CLAIM**

The ornamental design for an anti-skimming device, as shown and described.

DESCRIPTION

FIG. 1 is a top perspective view of an anti-skimming device showing my new design therefor;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and,

FIG. 7 is a right side view thereof.

In the drawings, the broken lines depict fold lines, which form part of the claimed design.
